UNITED STATES PATENT OFFICE

2,671,801

a,a, DISUBSTITUTED SUCCINIC ACIDS AND ANHYDRIDES

James M. Sprague, Drexel Hill, and Edward J. Cragoe, Jr., Ridley Park, Pa., assignors to Merck & Co., Inc., a corporation of New Jersey

No Drawing. Application November 4, 1949,
Serial No. 125,648

6 Claims. (Cl. 260—515)

1

This invention is broadly concerned with *a,a*-disubstituted succinic acids and derivatives thereof. It is more particularly concerned with new *a,a*-disubstituted succinic acids and anhydrides in which the substituents are chosen from the following radicals: alkyl and aryl, aryl and aryl containing at least one substituent.

The compounds of this invention can be represented by the general formulae:

and

in which R and R' are chosen from the above recited pairs of substituents.

The compounds of this invention have utility as intermediates for the production of various chemical compounds. Prior to this invention, the more complex *a,a*-disubstituted succinic acids were unknown and their availability, as a feature of this invention, opens a wide field for syntheses of new chemical compounds.

Further, certain of the compounds of this invention possess the characteristic of suppressing gastric secretion, which characteristic finds utility in the study and treatment of gastric ulcer. The *a,a*- diarylsuccinic acids in which one or both of the aryl nuclei are substituted by one or more chlorine atoms, are particularly useful in the suppression of gastric secretions. Additionally, other compounds of this invention possess antibacterial activity. Illustrative of the compounds possessing antibacterial activity are the *a*-aryl-*a*-alkyl-succinic acids and anhydrides in which the alkyl radical contains six or more carbon atoms.

Prior to this invention only the simpler *a,a*-dialkyl-succinic acids and anhydrides were known and of the diaryl type compounds only *a,a*-diphenylsuccinic acid was known. A feature of this invention is making available heretofore unknown *a*-aryl-*a*-alkyl-succinic acids and anhydrides and *a*-aryl-*a*(aryl containing at least one substituent)succinic acids and anhydrides. It is now possible to prepare these compounds by virtue of the availability of the intermediate di-substituted-alkylidenecyanoacetates described in

2

the co-pending application of Edward J. Cragoe filed herewith and entitled "Alkylidenecyanoacetates and an Improved Process for Preparation Thereof."

5 The compounds of this invention can be prepared by starting with the proper disubstituted-alkylidenecyanoacetate ester and treating it with hydrogen cyanide to produce the dicyano ester which can then be hydrolyzed successively by 10 sulfuric acid and an alkali to yield nitrogen free succinic acid. The corresponding succinic anhydrides can be obtained by refluxing the succinic acid with acetyl chloride or thionyl chloride and purifying the anhydride by distillation.

15 The reactions involved can be represented by the following equation:

in which (A) represents the alkylidenecyanoacetate, (B) the dicyano ester, (C) the succinic acid, and (D) the succinic acid anhydride. R and R' are the desired substituents on the succinic acid or acid anhydride and have the meanings heretofore set out.

In general the preparation of the cyano esters is accomplished by adding a saturated aqueous solution of potassium cyanide to an alcoholic 40 solution of the alkylidenecyanoacetate, warming the mixture for a few minutes and acidifying with hydrochloric acid. The dicyano esters are usually oils which are conveniently purified and in general characterized as their derivatives, that is the succinic acid or succinic acid anhydrides.

The hydrolysis of the dicyano esters is carried out by refluxing the ester with a mixture consisting of concentrated sulfuric acid, glacial acetic acid and some water. The refluxing is continued for approximately 12 to 15 hours. A satisfactory medium for the hydrolysis is sulfuric acid 50%, acetic acid 40%, and water 10%. After refluxing, the mixture is poured into water and the resulting oil extracted with benzene. 55 The benzene is removed by distillation, conven-

iently at reduced pressure, and the residual oil refluxed with 20% potassium hydroxide until ammonia is no longer liberated. At the end of this time the reaction mixture is cooled and acidified and the succinic acids separate. The acid can be recovered by filtration if a solid, or by extraction with benzene followed by removal of the benzene by distillation, if a liquid. The advantage of the alkaline hydrolysis is that nitrogen free succinic acids are obtained by this procedure.

The succinic acid anhydrides can be obtained by refluxing the corresponding succinic acid with acetyl chloride or thionyl chloride and purifying the anhydride by distillation.

The compounds embraced by this invention are illustrated by:

Compound	M. P., °C.	Physical Constants		
		B. P., °C.	Press, mm. Hg	n_D^{25}
α -phenyl- α -ethylsuccinic acid	148-9			
α -phenyl- α -n-amylsuccinic anhydride		162	1	1.5159
α -phenyl- α -n-heptylsuccinic anhydride		170-2	2	1.5081
α -phenyl- α -n-undecylsuccinic anhydride		193-6	1-2	1.5010
α -phenyl- α -(2-cyclohexylethyl) succinic anhydride		185-8	1-2	1.5301
α -phenyl- α -(5-cyclohexylpentyl) succinic anhydride		210	1-2	1.5210
α -(4-n-butylphenyl)- α -n-hexylsuccinic anhydride	95-8	178-180	1-2	1.5055
α -diphenylsuccinic acid	155-6			
α -phenyl- α -(4-chlorophenyl) succinic acid	187-8			
α -(4-chlorophenyl)- α -(2-chlorophenyl)succinic acid	195-6			
α -di-(4-chlorophenyl)-succinic acid	188-9			

¹ Taken on supercooled liquid.

The invention is illustrated by but not necessarily restricted to the following preferred embodiments:

Example 1.— α -Phenyl- α -(2-cyclohexylethyl) succinic acid.—Ethyl 1-phenyl-3-cyclohexylpropylidenecyanoacetate (61 gm., 0.196 mole) was dissolved in ethanol (80 ml.) and treated with a solution of potassium cyanide (25.5 gm., 0.39 mole) in water (80 ml.). The orange solution was heated, with stirring, on a steam bath for 15 minutes, then cooled, diluted with water (100 ml.) and acidified with excess concentrated hydrochloric acid. The oily layer that separated was extracted with benzene (three 75 ml. portions) and the combined extracts washed with water. The benzene was removed by distillation at reduced pressure. The residual oil (66 gm. 99%) is ethyl 2,3-dicyano-5-cyclohexyl-3-phenylpentanoate. This material was added to a solution composed of concentrated sulfuric acid (248 gm.) glacial acetic acid (262 gm.) and water (50 ml.). The mixture was refluxed for 15 hours and then poured onto crushed ice (640 gm.). The oily layer that separated was removed by benzene extraction (three 100 ml. portions). The benzene was removed by distillation from the combined extracts and the residual oil treated with 20% potassium hydroxide (185 ml.). The resulting solution was refluxed for 72 hours. After cooling, the solution was treated with decolorizing carbon, filtered and the filtrate acidified with excess hydrochloric acid. The oily α -phenyl- α -(2-cyclohexylethyl) succinic acid that separated was removed by extraction with benzene (three 100 ml. portions). The combined extracts were washed with water and dried over anhydrous magnesium

sulfate. After removal of the benzene by distillation at reduced pressure, a waxy solid remained, yield, 59.6 gm. (94%), M. P., 100-110° C.

The α -phenyl- α -(2-cyclohexylethyl) succinic acid was refluxed for 2 hours with acetyl chloride (75 ml.). The excess acetyl chloride was removed by distillation and the residue fractionated at reduced pressure. The yield of material boiling at 184-8° C. at 1-2 mm. of Hg is 30.4 gm. (54%). Refractionation gives 29.3 gm. (52%) of material boiling at 185-8° C. at 1-2 mm., n_D^{25} = 1.5301.

Example 2.— α -Phenyl- α -(n-heptyl) succinic anhydride is prepared from ethyl 1-phenyl-octylidenecyanoacetate in a manner similar to that described in Example 1. The yield was 56%; B. P., 170-2° C. at 2 mm. of Hg; n_D^{25} , 1.5081.

Example 3.— α -Phenyl- α -(5-cyclohexylpentyl) succinic anhydride was prepared from ethyl 1-phenyl-6-(cyclohexyl) hexylidenecyanoacetate in a manner similar to that described in Example 1. The yield was 45%; B. P. 210° C. at 1-2 mm. of Hg; n_D^{25} , 1.5210.

Example 4.— α -(4-n-butylphenyl)- α -(n-hexyl) succinic anhydride is prepared from ethyl 1-(4-n-butylphenyl)-heptylenecyanoacetate in a manner similar to that described in Example 1. The yield is 54%, M. P. 95-8° C., B. P. 178-180° C. at 1-2 mm. of Hg, n_D^{25} , 1.5055 (on supercooled liquid).

Example 5.— α -Phenyl- α -(4-chlorophenyl) succinic acid.—Ethyl phenyl(4-chlorophenyl) methylenecyanoacetate (101.4 gm., 0.326 mole) was dissolved in warm ethanol (147 ml.) and treated with a solution of potassium cyanide (42.4 gm., 0.65 mole) in water (180 ml.). The clear yellow solution that resulted was heated on a steam bath, with stirring, for 15 minutes. The solution was cooled and acidified with excess concentrated hydrochloric acid. The product separated nearly quantitatively as a viscous oil. The mixture was diluted with water and extracted with benzene (three 100 ml. portions). The benzene was removed by distillation at reduced pressure. The residual oil, ethyl 3-phenyl-3-(4-chlorophenyl)-2-3-dicyanopropionate, weighed 109 gm. (99%).

This ethyl 3-phenyl-3-(4-chlorophenyl)-2-3-dicyanopropionate was added to a mixture of glacial acetic acid (431 gm.) concentrated sulfuric acid (409 gm.) and water (83 ml.). The mixture was refluxed for 15 hours, cooled and poured onto ice (1 kgm.). The oil which separated soon solidified. This material was removed by filtration, washed with water and dissolved in 20% potassium hydroxide solution (305 ml.). The solution was refluxed for 72 hours, cooled, diluted with water (300 ml.), treated with decolorizing charcoal and filtered. The filtrate was acidified with excess hydrochloric acid; the oil that separated soon solidified.

The yield of crude α -phenyl- α -(4-chlorophenyl)-succinic acid was 98.5 gm. (100%), M. P. 155-157° C. Successive recrystallizations from a mixture of acetic acid and water gave 75.7 gm. (77%) of product melting at 187-188° C.

Example 6.— α -(2-chlorophenyl)- α -(4-chlorophenyl) succinic acid, is prepared from ethyl (2-chlorophenyl)-4-(4-chlorophenyl)-methylene-cyanoacetate in a manner similar to that described in Example 1. The yield was 47%; M. P. 195-6° C.

Similarly α -phenyl- α -(2-chlorophenyl) succinic acid can be prepared from ethyl phenyl(2-chlorophenyl) methylenecyanoacetate.

Further, by using procedures similar to Ex-

ample 1, and similar molar portions of ethyl 1-(4-hydroxyphenyl)propylidenecyanoacetate, ethyl phenyl-(4-methoxyphenyl)methylene-cyanoacetate, ethyl 9-fluorenylidene-cyanoacetate, ethyl 2-camphanylidenecyanoacetate, and ethyl 3,3-dimethyl-2-butylidene-cyanoacetate, it is possible to obtain respectively α -ethyl- α -(4-hydroxyphenyl)succinic acid, α -phenyl- α -(4-methoxyphenyl)succinic acid, 9-carboxyfluorene-9-acetic acid, 2-carboxycamphane-2-acetic acid, and α -methyl- α -t-butylsuccinic acid.

It is to be realized that in the hydrolysis of the intermediate dicyano compounds possessing an aryl nucleus containing a labilizing group (such as hydroxy or methoxy) milder acid conditions are desirable. For example, a suitable hydrolysis medium for 2,3-dicyano-3-phenyl-3-(4-hydroxyphenyl)propionate consists of concentrated sulfuric acid (35%), glacial acetic acid (35%) and water (40%). Milder hydrolysis media can be chosen from solutions obtained by diluting a solution of 6 parts by weight concentrated sulfuric acid and 4 parts of water with up to six parts of glacial acetic acid.

In the specification and claims, the term "aryl" is intended to embrace phenyl or substituted phenyl radicals and the term "aralkyl" to embrace phenalkyl or substituted phenalkyl radicals, the substituent group, in either case, being of the type hereinbefore mentioned.

What is claimed is:

1. α -Phenyl- α -(mono-halophenyl)succinic acids.
2. α -Phenyl- α -(mono-chlorophenyl)succinic acids.
3. α -(2-chlorophenyl)- α -(4-chlorophenyl)succinic acid.
4. α -(lower-alkyl)- α -phenylsuccinic acids.
5. α -Phenyl- α -(5-cyclohexylpentyl)succinic acid.

5
10

6. A compound chosen from the class consisting of

and

15 in which R and R' are selected from the groups consisting of (1) where R is lower alkyl and R' is a phenyl radical, (2) where R and R' respectively is a phenalkyl radical and (3) R and R' respectively is a phenyl radical and at least one 20 phenyl nucleus is mono-halo substituted.
